[57] CLAIM

The ornamental design for a children's computer keyboard, as shown and described.

DESCRIPTION

FIG. 1 is a perspective view of the children's computer keyboard embodying the design of the present invention;

FIG. 2 is a front elevational view thereof;

FIG. 3 is a rear elevational view thereof;

FIG. 4 is a side elevational view thereof;

FIG. 5 is a side elevational view thereof opposite that shown in FIG. 4;

FIG. 6 is a top plan view thereof, and,

FIG. 7 is a bottom view thereof.

FIGS. 2-7 are drawn on an enlarged scale.

FIG. 1

FIG. 2.

FIG. 4.

FIG. 3.

FIG. 5.

FIG. 6.

FIG. 7.
